UNITED STATES PATENT OFFICE.

GEORGE GILL, OF STRATFORD, AND EDWIN L. BRITTIN, OF DERBY,
ASSIGNORS TO ROGERS & BRITTIN SILVER COMPANY, OF BRIDGE-
PORT, CONNECTICUT.

DESIGN FOR SPOON AND FORK HANDLES.

SPECIFICATION forming part of Design No. 11,778, dated May 18, 1880.

Application filed April 16, 1880. Term of patent 7 years.

To all whom it may concern:

Be it known that we, GEO. GILL, of Stratford, county of Fairfield, and EDWIN L. BRITTIN, of Derby, in the county of New Haven and State of Connecticut, have invented a new Design for Spoon and Fork Handles; and we do hereby declare the following, when taken in connection with the accompanying drawing and the letters of reference marked thereon, to be a full, clear, and exact description of the same, which said drawing constitutes part of this specification, and represents a face view.

This invention relates to a design for spoon and fork handles; and it consists in the ornamentation as shown in the accompanying illustration.

The handle is in outline what is known as the "Gothic" or "lancet" shape.

From the tip to about midway of the length of the handle the surface is left plain without

ornamentation. At about the central part of the handle is the representation of a crown, and at the base of the handle is a similar crown-like ornament inverted. On the edge 25 of the handle, between the two crowns, is a bead, and the surface between the two beads is ornamented by diaper-work, as shown in the accompanying illustration.

I claim—

The design for spoon-handle, consisting of the plain surface portion with the central crown - shaped ornament, and the inverted crown-shaped ornament at the base, with the beads and intermediate ornamentation between the said crown-shaped ornaments, as shown in the accompanying illustration.

GEORGE GILL.
EDWIN L. BRITTIN.
